UNITED STATES PATENT OFFICE.

EDGAR J. HAHN, OF ST. LOUIS, MISSOURI.

DESIGN FOR A MEDAL.

SPECIFICATION forming part of Design No. 22,675, dated August 8, 1893.

Application filed March 30, 1893. Serial No. 468,403. Term of patent 3½ years.

To all whom it may concern:

Be it known that I, EDGAR J. HAHN, of the city of St. Louis, in the State of Missouri, have invented and produced a new and original 5 Design for Medals, of which the following is a specification, reference being had to the accompanying drawings, showing a part thereof.

Figure 1 represents the view of one face of the medal, the opposite face being a duplication 10 of the one shown. Fig. 2 is a central cross sectional elevation of the medal.

The leading features of my design duplicated on each face of the medal may be described as follows: The central figure is a face 15 of the Aztec sun shown in relief, qualified by showing the cheeks slightly distended, the tongue protruding, and the upper set of teeth showing fully. Around the face is a raised circle containing the symbolic outlines of the 20 twenty days of the Aztec month; surrounding this circle are eight raised triangular figures or symbols of the sun's rays. Surrounding the raised circle and intermediate of the

several triangles are the raised outlines of the symbolic representations of the Aztec days of 25 the year (two hundred and sixty in number). Around the apices of the triangles is an outer circle or border in relief the raised portions or figures thereof corresponding to the outlines of certain portions of the Aztec calendar 30 not yet fully understood by archaeologists. On the edge of the outer circle or border and immediately over the triangle above the head of the central figure or face is a ring completing the design.

Having described my invention, what I 35 claim is—

The design for a medal substantially as herein described.

In testimony whereof I affix my signature in 40 the presence of two witnesses.

EDGAR J. HAHN.
